DESIGN FOR A POT HANDLE

Martin E. Behl, New York, N. Y.

Application October 18, 1944, Serial No. 115,837

Term of patent 7 years

(Cl. D44—29)

To all whom it may concern:

Be it known that I, Martin E. Behl, a citizen of the United States, residing at New York, in the county and State of New York, have invented a new, original, and ornamental Design for a Pot Handle, of which the following is a specification, reference being had to the accompanying drawing, forming part thereof.

Fig. 1 is a top plan view of a pot handle showing my new design;

Fig. 2 is a side elevation of the same; and

Fig. 3 is an end elevation of the same.

I claim:

The ornamental design for a pot handle, substantially as shown.

MARTIN E. BEHL.
